SHIPPING CONTAINER FOR MICROSCOPIC SLIDES OR THE LIKE

Niels Kristian Johan Christiansen, 20 Vesterbrogade,
1620 Copenhagen, Denmark

Filed Feb. 9, 1971, Ser. No. 114,095

Claims priority, application Denmark Dec. 23, 1970

Term of patent 14 years

Int. Cl. D3—07

U.S. Cl. D87—1 D

FIG. 1

FIG. 2

FIG. 1 is a perspective view of a shipping container for microscopic slides or the like showing my new design, in an open position; and

FIG. 2 is a perspective view thereof in a closed position. The side opposite that seen in FIG. 2 is substantially the same in appearance as the side shown.

I claim:

The ornamental design for a shipping container for microscopic slides or the like, as shown and described.
